UNITED STATES PATENT OFFICE.

EDWARD E. SHEAR, OF KINGSTON, NEW YORK.

BAGGAGE-CAR DOOR.

Application filed November 12, 1923. Serial No. 674,283.

To all whom it may concern:

Be it known that I, EDWARD E. SHEAR, a citizen of the United States, residing at Kingston, in the county of Ulster and State 5 of New York, have invented certain new and useful Improvements in Baggage-Car Doors; and I do declare the following to be a full, clear, and exact description of the invention, such as will enable others skilled 10 in the art to which it appertains to make and use the same.

It is common practice to slidably mount the doors of baggage cars and these doors are very often left open to some extent while 15 the train is in motion, for instance for ventilation. A number of serious accidents have occurred, due to sudden stoppage of the train, when an occupant of the baggage car is looking or leaning out of the partially 20 open door, as when such stoppage occurs, the door often slides forcibly shut. It is the object of my invention however to provide an improved form of baggage car door having a supplemental section which may be 25 opened, without danger of this section or the main section of the door slamming shut when the train is suddenly stopped.

With the foregoing in view, the invention resides in the novel subject matter herein- 30 after described and claimed, the description being supplemented by the accompanying drawings.

Figure 1 is a side elevation showing the door completely closed.

Figure 2 is a view similar to Fig. 1, but showing the supplemental section of the door swung open.

Figure 3 is an upper edge view showing the parts in the position of Fig. 1.

Figure 4 is an upper edge view with the parts standing as shown in Fig. 2.

Figure 5 is a view similar to Fig. 4 but illustrating the door slid partially open.

Figures 6 and 7 are detail horizontal sec- 45 tional views on lines 6-6 and 7-7 of Figs. 1 and 2, respectively.

Figure 8 is a detail vertical section on line 8-8 of Fig. 6.

In the drawings above briefly described, 50 the numeral 1 designates one side of a baggage car, said side having the usual door opening above which a horizontal track 2 is rigidly mounted. Hangers 3 are engaged with this track and suspend a main, relatively large, door section 4 therefrom, the lower edge of this section being grooved at

5 to receive a guide rail 6 secured to the sill of the door frame. A supplemental, relatively small door section 7 is connected by hinges 8 with one end of the door section 4 60 and co-operates therewith in constituting a complete door.

Above the door sections 4 and 7, I have shown a horizontal plate 9 rigidly secured to the side of the car, said plate being illustrated with an upstanding flange 10 through which bolts or screws 11 pass to secure it in place. The plate 9 is provided with an inner edge 12 which constitutes a stop to be engaged by one of the hangers 3, so that the 70 main door section 4 cannot move from its normal, closed position, when the door 7 is swung open, that is, said door section 4 cannot move in a direction to close the portion of the door opening which is normally 75 closed by the supplemental section 7. The plate 9 is formed with an arcuate slot 13 which is concentric with the axis of the hinges 8, when the door stands closed. This slot opens in the direction in which the door 80 moves when the latter is opened, and the opposite side walls 14 and 15 of said slot, constitute arcuate tracks concentric with the hinges 8. An upstanding shoe 16, on the supplemental door section 7, is received in 85 the slot 13 to engage the tracks 14 and 15 and it will be seen by reference to Figs. 3 and 4, that when the door section 7 is closed, the tracks and shoe will hold the entire door against opening, but when said section 7 is 90 swung inwardly against the inner side of the main section 4, the shoe 16 leaves the slot 13, so that the entire door may be slid open if desired. If it is necessary or advisable to have the door section 7 in an open position, 95 when the train is in motion, it will be absolutely safe for an occupant of the car to lean out of the opening, previously closed by said section 7, as sudden stoppage of the train, cannot slam the door shut and injure 100 him.

To hold the door section 7 against the section 4, when the former is swung inwardly against the latter, I preferably provide a straight horizontal track 17 which is 105 suitably supported and extends from the plate 9, substantially co-incident with the track 15. This track 17 is engaged by the shoe 16 as the door slides open, as shown in Fig. 5 and thus the sections 7 and 4 are held 110 against each other.

In connection with the features above de-

- scribed, I preferably secure a short arcuate track 18 to the sill of the door frame or the floor of the car for reception in an arcuate groove 19 in the lower end of the supplemental door section 7. If desired, the door section 7 may be provided with spaced plates 20 to engage the track 18 and if desirable, the latter may be undercut to engage said plates, as shown in Fig. 8.
- 10 By providing the comparatively simple and inexpensive construction above described, a greatly improved baggage car door is provided, which will be a protection against injury, by accidents such as above set forth.
- 15 As excellent results are obtainable from the details disclosed, they are preferably followed, but within the scope of the invention as claimed, numerous minor changes 20 may be made.

I claim:

1. A baggage car door comprising a main slidably mounted door section, a supplemental door section carried by said main section 25 and movable to an open position without sliding said main section from its normal closed position, and stationary trackage engaging said supplemental section and preventing the entire door from sliding longitudinally when said supplemental section is closed, and also preventing closing movement of said main section beyond its normal closed position when said supplemental section is open.
- 30 2. A door comprising a slidably mounted main section, a supplemental section hinged on a vertical axis to said main section and inwardly foldable against the inner side thereof, and stationary arcuate trackage concentric with the aforesaid axis when the door is closed, said supplemental section having a shoe engaged with said trackage to hold the entire door closed until said supplemental section is swung inwardly on said main section.
- 35 3. A door comprising a slidably mounted main section, a supplemental section hinged on a vertical axis to said main section and inwardly foldable against the inner side 40 thereof, inner and outer arcuate tracks stationarily mounted and concentric with the aforesaid axis when the door is closed, and a shoe carried by said supplemental section and received between said tracks when the 45 door is closed, said shoe being disengageable

from said tracks when said supplemental section is swung inwardly against said main section.

4. A structure as specified in claim 2; together with a straight horizontal track leading from said arcuate trackage, in parallel relation with the main door section, said shoe being engageable with said straight track as the door is slid open to hold the supplemental door section against the main section.

5. A structure as specified in claim 3; together with a straight horizontal track leading from said outer arcuate track in parallel relation with the main door section, said shoe being engageable with said straight track as the door is slid open to hold the supplemental door section against the main section.

6. A door comprising a slidably mounted main section, a supplemental section hinged on a vertical axis to said main section and inwardly foldable against the inner side thereof, a horizontal plate stationarily mounted at the upper end of the door and having an arcuate slot concentric with the aforesaid hinge axis when the door is closed, said slot opening in the direction in which the door slides on its opening movement, and a shoe carried by said supplemental section and received in said slot when the door is closed.

7. A structure as specified in claim 6; together with a horizontal track secured to said plate substantially co-incident with the inner edge of said slot and extending therefrom in parallel relation with the main door section, said shoe being engageable with said track as the door is slid open to hold the supplemental door section against the main section.

8. A door comprising a slidably mounted main section, a supplemental section hinged on a vertical axis to said main section and inwardly foldable against the inner side thereof, and a stationary arcuate track concentric with the aforesaid axis when the door is closed, said supplemental section having a groove in which said track is received until said supplemental section is swung inwardly against said main section.

In testimony whereof I have hereunto affixed my signature.

EDWARD E. SHEAR,
